(57) CLAIM

The ornamental design of casual lounge seating, as shown and described.

DESCRIPTION

FIG. 1 is a right side perspective view of casual lounge seating incorporating our new design, wherein the portions in phantom illustrate environment and form no part of the claimed design;

FIG. 2 is a front elevation view thereof;

FIG. 3 is a right side elevation view thereof, wherein the left side elevation view is a mirror image;

FIG. 4 is a top plan view thereof;

FIG. 5 is a rear elevation view thereof; and,

FIG. 6 is a bottom plan view thereof.
